(57) **CLAIM**

I claim the ornamental design for a curved soundbar, as shown and described.

DESCRIPTION

FIG. 1 is a front perspective view of the curved soundbar; FIG. 2 is a front view of the curved soundbar; FIG. 3 shows a rear view of the curved soundbar; FIG. 4 shows a first side-on view of the curved soundbar; FIG. 5 shows a second side-on view of the curved soundbar; FIG. 6 shows a top view of the curved soundbar; and, FIG. 7 shows a bottom view of the curved soundbar. The broken lines shown are included for the purpose of illustrating portions of the curved soundbar that form no part of the claim.
